Attorneys

UNITED STATES PATENT OFFICE.

ERWIN E. MILLER, OF FULLERTON, CALIFORNIA.

EXPANSIBLE PACKING.

Application filed June 9, 1924. Serial No. 718,798.

This invention is a self expanding packing for pump plungers and the like, and consists of the novel features herein shown, described and claimed.

5 An object is to make a pump plunger having a self expanding packing operated by the pressure to take up the wear.

Another object of this invention is to provide a flexible, expandable packing, so constructed as to act as a valve permitting the fluid under pressure to pass behind the packing and force the same against the wall of the cylinder, substantially with the same pressure as the fluid pumped, there being a 15 port on either end of the packing, which is automatically opened as the plunger is reciprocated.

Other objects and advantages will appear from the drawings and specification.

20 The drawing illustrates a self expanding packing embodying the principles of my invention.

Figure 1 is a fragmentary diametrical longitudinal sectional detail of a pump cylinder and pump plunger having a self expanding packing.

Fig. 2 is a cross section on the line 2—2 of Fig. 1.

Fig. 3 is a cross section on the line 3—3 of Fig. 1.

Fig. 4 is an end view looking in the direction indicated by the arrow 4 in Fig. 1.

Fig. 5 is an end elevation of the self expanding packing shown in Fig. 1, the view being taken looking in the direction indicated by the arrow 5 in Fig. 6.

Fig. 6 is a sectional detail on the line 6—6 of Fig. 5 and on a plane parallel with Fig. 1.

The details of the self expanding packing 40 and the pump plunger shown in the drawings are as follows:

The pump cylinder 1 and the plunger rod 2 may be of any of the usual constructions. The plunger head 3 fits upon the tapered portion 4 of the plunger rod 2. A sleeve 5 extends from the head 3 around the rod 2. Ports 6 are formed through the head 3 outside of the plane of the sleeve 5, and peripheral grooves 7 are formed longitudinally in 50 the sleeve 5.

The self expanding packing 8 has a peripheral bearing surface 9 adapted to fit in the cylinder 1, and has a flat end face 10 fitting against the side of the head 3 and 55 covering the ports 6. The packing 8 has a flat face 11 at the opposite side from the face

10 and a central opening 12 surrounded by the material having the face 10 and a central opening 13 surrounded by the material having the face 11, the openings 12 and 13 being in longitudinal alignment, and there being an annular internal channel 14 extending outwardly from the longitudinal plane of the openings 12 and 13 and centrally located between the faces 10 and 11 to form 60 the yielding walls 15 and 16. The entire body of the packing is preferably of good soft rubber. Ribs 17 extend outwardly from the sleeve 5 to fit in the opening 12 and center the packing. 70

A second plunger head 18 fits upon the small end of the plunger rod 2 and against the face 11 of the packing, and has ports 19 covered by the wall 16, and a sleeve 20 extends from the head 18 and fits against the 75 end of the sleeve 5 and has grooves 21 and ribs 22 corresponding to the grooves 7 and ribs 17. Lock nuts 23 and 24 are screwed upon the end of the plunger rod 2 against the head 18. 80

The packing 8 is to be squeezed between the heads 3 and 18, to secure a tight fit.

The operation is as follows:

When the plunger goes down in the direction indicated by the arrow 25, the fluid pressure, either liquid or air, will pass through the ports 19 against the face 11, the wall 16 will give towards the channel 14 and the pressure will pass between the head 18 and the face 11 through the grooves 21 to the 85 channel 14, and the radial pressure in the channel 14 will expand the packing to press the peripheral bearing surface 9 against the inner face 26 of the cylinder 1, and the pressure will be exerted against the inner face 95 of the wall 15 to close the ports 6. When the movement of the plunger is reversed, the pressure will pass through the ports 6, the wall 15 will give, and the pressure will hold the wall 16 to close the ports 19 and expand 100 the packing against the face 26 of the cylinder, and this pressure will continually expand the packing against the face of the cylinder until the packing is worn out.

Thus I have produced a pump plunger 105 having packing adapted to be expanded by the pump pressure to take up the wear on the packing, the plunger comprising a plunger rod, plunger heads upon the rod, a packing between the plunger heads, there 110 being ports through the plunger heads to conduct pump pressure to the interior of the

packing to expand the packing, the packing being adapted to close the upper ports on a down stroke and the lower ports on an up stroke.

5. Various changes may be made without departing from the spirit of the invention as claimed.

I claim:

1. A pump plunger comprising a plunger rod, a pair of plunger heads having abutting hubs with a plurality of peripheral grooves formed therein mounted on said plunger rod, a flexible packer having an internal recess between flanges engaging the 15 hubs of said plunger heads, there being a plurality of ports in each plunger head adapted to conduct fluid within the pump cylinder to the internal recess in the flexible packer and nuts on said plunger rod 20 for holding said plunger heads together.

2. A pump plunger comprising a plunger rod having a tapered portion and a straight portion, a plunger head having a hub projecting from a flat face mounted on the 25 tapered portion of said plunger rod, a second plunger head having a hub projecting from a flat face abutting the hub of the first plunger head and mounted on the straight portion of said plunger rod, a 30 flexible packer having an internal recess between openings engaging the hubs of the first and second plunger heads and flat end faces engaging the flat faces of the first and second plunger heads, there being a plurality of peripheral grooves in the hubs of 35

the first and second plunger heads and a plurality of ports in each of said plunger heads, and nuts carried by said plunger rod for holding said plunger heads together.

3. A pump plunger comprising a plunger 40 rod, a pair of heads having ports therethrough secured to the plunger rod, means disposed between the heads for keeping the heads properly spaced on the plunger rod, and an expansible packing disposed between 45 the heads having an internal annular recess defining flanges which cover said ports and which bear against said means, there being passages formed in said means beneath said flanges.

4. A pump plunger comprising a plunger rod, a pair of heads having ports therethrough secured to the plunger rod, said heads having projecting hubs disposed in abutting relation about said plunger rod for 50 keeping the heads properly spaced thereon, an expansible packing disposed between the heads having an internal annular recess formed thereon defining flanges which cover said ports and which bear against said hubs, 55 and means providing passages upon said hubs beneath said flanges.

5. A head for plungers comprising a head having a projecting hub, there being apertures formed through the head and grooves 60 formed on the peripheral surface of the hub as and for the purpose described.

In testimony whereof I have signed my name to this specification.

ERWIN E. MILLER.
